SKATE SHARPENER

Raymond H. De Witt, Plymouth, Ohio, assignor to The Fate-Roof-Heath Company, Plymouth, Ohio, a corporation of Delaware

Filed July 20, 1962, Ser. No. 211,236

11 Claims. (Cl. 51—96)

This invention relates generally, as indicated, to a skate sharpener and more particularly to an ice skate sharpening grinding machine which can be employed quickly and easily to produce new sharp edges along the full length of the ice skate runner.

Heretofore, especially with less expensive skates, the blade is sharpened simply by cross grinding the entire length of the blade face. This type of grinding operation will leave cross grinding marks which, of course, cause undue skating friction. However, with higher quality skates, it is required that these cross grinding marks be removed and, moreover, the desired amount of hollow grind be produced on the skate runner. The amount of hollow grind produced on the skate runner, will vary in radius depending upon the principal use to which the skate is to be put. Thus, figure skates will normally have a smaller radius of curvature for the hollow grind and speed skates will have a substantially larger radius of curvature. It can then be seen that the sharpening of skate blades by modern high quality standards is an operation requiring at least two types of grinding passes with the work properly disposed to the grinding wheel.

It is accordingly a principal object of the present invention to provide an ice skate sharpener which can be employed quickly and easily to produce the desired sharp edges on the skate runner.

It is another important object of the present invention to provide a grinding machine for sharpening ice skates having two grinding wheels for performing cross grinding and parallel grinding, respectively, and a clamping fixture for such ice skates which will hold the work properly with respect to both wheels.

A further object is the provision of a grinding machine for the sharpening of ice skates which can place the desired sharp skating edges on the skate blade runner with but two simplified grinding operations.

A still further object is the provision in such a sharpener of a unique skate blade clamp and holder which will properly position the blade for both grinding operations and which will permit complete visual access to the runner face being ground.

Other objects and advantages of the present invention will become apparent as the following description proceeds.

To the accomplishment of the foregoing and related ends, the invention, then, comprises the features herein-after fully described and particularly pointed out in the claims, the following description and the annexed drawings setting forth in detail a certain illustrative embodiment of the invention, this being indicative, however, of but one of the various ways in which the principle of the invention may be employed.

In said annexed drawings:

FIG. 1 is a fragmentary front elevation of a skate sharpener in accordance with the present invention partially broken away and in section;

FIG. 2 is a top plan view of such skate sharpener;

FIG. 3 is a fragmentary side elevation of such skate sharpener as seen from the left in FIG. 1 with the wheel dresser being removed from the wheel surface and the skate blade clamping mechanism not shown;

FIG. 4 is an end elevation of the opposite side of the skate sharpener as seen in FIG. 3 with the wheel dresser

2

removed for clarity of illustration and the skate blade clamping mechanism now shown;

FIG. 5 is a side elevation including the blade clamp mechanism showing the grinding head assembly in its alternative position for the parallel grinding operation;

FIG. 6 is a detail view of the mounting of the grinding head assembly partially broken away and in section;

FIG. 7 is a similar detail view of such mounting as seen from the left in FIG. 6; and

FIG. 8 illustrates the manner in which the skate runner may be clamped in the holder by means of a springing bar properly to straighten the runner.

Referring now to the annexed drawings and more particularly to FIG. 1, it will be seen that the illustrated skate sharpener in accordance with the present invention comprises five basic components which for conveniences of shipping may be readily separated. The first is a relatively heavy circular floor base 1 supporting centrally therein a pedestal pipe 2, which, of course, in the broken away illustration of FIG. 1, is greatly foreshortened. On top of the pedestal pipe 2, there may be provided a support shaft and arm assembly indicated generally at 3 with such arm assembly supporting at its distal end an ice skate holding clamp assembly 4. A grinding head assembly 5 is then mounted on such support shaft and arm assembly coaxially aligned with the pedestal pipe 2 and base 1.

To assemble the skate sharpener, the pedestal pipe 2 is placed in the floor stand or base 1 and secured by set screws or the like and the support shaft 6 of the shaft and arm assembly 3 may then be secured to the pedestal pipe 2 by suitable fasteners such as Allen set screws 7 provided in adapter 8. The ice skate holding clamp 9 may then be positioned at the distal end of the second arm 10 which is mounted for swinging movement about a vertical axis at the distal end of the first arm 11. A trunion knuckle 13 is provided at the top of shaft 6 accommodating an axle shaft 14 extending horizontally therethrough. Angles 15 and 16 are secured to each end of the axle shaft 14 by screws or the like 17. The outwardly directed flanges of the angles 15 and 16 may then be secured to the main base 18 for the motor 19 of the grinding head assembly 5 by suitable fasteners as shown at 20. In this manner, the various components of the skate sharpener may quickly and easily be assembled and disassembled.

The motor 19 of the grinding head assembly drives a pulley 22 (see FIG. 2), and a V-belt 23 may be trained about such pulley and pulleys 24 and 25 mounted on drive shafts 26 and 27, respectively, driving grinding wheels 28 and 29. Such pulleys and belt may be enclosed in a guard 30 held to the grinding head base by elongated fasteners 31 and 32. Bearings for the shafts 26 and 27 are provided in housings 34 and 35 supported beneath the base in its position shown in FIGS. 3 and 4, for example. As seen more clearly in FIG. 1, each of the grinding wheels 28 and 29 is provided with a semi-circular guard shown at 36 and 37 respectively. Such guards may be fastened to the base 18 by the screws indicated at 39 in FIG. 3. The motor 19 is mounted between uprights 40 and 41 of a special motor mount 42 which is supported on rearwardly extending plate 43 with both the mount and the plate being held to the base 18 by the fastening means 20. It can now be seen that the motor 19 is effective to drive both grinding wheels 28 and 29

60 by means of the belt pulley drive shown. Cap screws or the like 44 may be employed to hold the bearing housings and arbor assemblies to the base 18 (note FIG. 4) and in place of one of such cap screws, a rotating handle 45 having a knob 46 on the outer end thereof may be provided held in place by lock nut 47. In this manner, a handle is provided to pivot the grinding head assembly about the axis of the knuckle axle shaft 14 to move the

grinding head assembly from the FIG. 4 position to the FIG. 5 position, for example. A similar clamping screw 59 in the knuckle 13 may be operated by handle 51 properly to lock the axle 14 and thus the grinding head assembly in the desired selected position with the grinding wheels in either a vertical or horizontal plane. As seen in FIG. 7, a leveling screw 52 may be provided in a bracket 53 acting as a stop properly to support the grinding head in its upright position with the wheels in a vertical plane. The plate 43 at its outer end may be provided with a further leveling screw 54, the head of which will engage the shaft 6 in the position shown in FIG. 5 wherein the grinding wheels are in a horizontal plane. It is here noted that the pivot axis of the knuckle axle shaft 14 coincides with the horizontal plane of the axes of arbors 26 and 27. Moreover, the grinding wheels 28 and 29 are aligned at their midpoints with the axis of such knuckle axle shaft. Thus a blade presented to the face of grinding wheel 29 for cross grinding in the horizontal plane of the axle 27 in FIG. 4, for example, can also be presented in the same plane to the face of the grinding wheel 28 when in the FIG. 5 position for a parallel grinding operation.

The wheel 28 may, for example, be a six inch by quarter inch rubber grinding wheel and the wheel 29 may be a harder four inch by three-quarter inch grinding wheel for the cross grinding operation. Both wheels are held to the respective arbors by the nuts and adapters illustrated at 55 and 56. The smaller grinding wheel 29 has a built-in diamond dresser indicated generally at 58 in FIG. 1 which produces a convex radius on the face of the wheel as shown in FIG. 2. It has been found not necessary to maintain this particular convex shape to use the wheel, but it is necessary to maintain this wheel perfectly round to get the proper results. The dresser is mounted on a semi-circular member 59 which is pivoted at opposite ends by means of screws 60 and 61 to diametrically opposite portions of the guard 37, the axis of such pivots 60 and 61 intersecting the axis of the arbor 27. To use the dresser 58, the lock nut 62 is loosened and the threaded dresser is then fed into the wheel while rotating the dresser back and forth about the pivots 60 and 61.

The cap screws 44 holding the bearing housing 33 for the arbor 26 also pass through a bracket 65 for the illustrated radius type diamond dresser for the horizontal rubber grinding wheel 28. A tubular member 66 may be welded on top of the upstanding portion of the bracket 65 and the dresser shaft 67 extending through such tubular member may be provided with set collars at each end of such tubular member as shown at 68 and 69. The proximal end of arm 70 is secured to the end of shaft 67 and a dresser holder 71 is secured to the outer end of the arm 70 by a suitable fastener such as the cap screw shown. A dresser barrel assembly 73 is mounted in the holder and includes an eccentric bar 74 with the diamond dresser 75 being threadedly mounted in the end thereof. The barrel assembly 73 is held in the support housing 71 and positioned by tightening or loosening the thumb screw 76 provided therein. The dresser assembly will normally be in its out-of-the-way position as shown in FIGS. 3 and 5 and may be unlocked by using the T-handle locking screw 78 mounted in the sleeve 66 and rotated around the axis of shaft 67 to the position shown in FIGS. 1 and 2. When thus properly positioned, the feeding of the dresser into the grinding wheel can be accomplished by loosening the thumb screw 76 and moving the dresser barrel assembly 73 through the support housing 71 slightly, thus increasing the amount of contact with the grinding wheel. The dresser, however, must make contact with the grinding wheel below center of its radius so that when the assembly is moved further through the support housing, it engages more of the grinding wheel. Throughout the dressing operation, the dresser is rotated back and forth on the axis of the barrel assem-

bly past the grinding wheel until the desired results are obtained.

The amount of convex face, which is in turn the amount of hollow grind produced on the skate runner, is controlled by the amount the diamond dresser 75 is adjusted to extend through the dresser holding bar 74. The hollow grind can be gauged by the curvature of three coins, a quarter, half dollar, or silver dollar, held at right angles to the skate blade. The hollow grind to match the curvature of a quarter is used for figure skates and is obtained by extending the diamond dresser $\frac{5}{16}$ of an inch through the holder 74. The curvature of the half dollar is most commonly used and is obtained by extending the dresser through the holder $\frac{3}{16}$ of an inch. Speed skaters may prefer a silver dollar hollow grind which is obtained by extending the diamond dresser only $\frac{1}{16}$ of an inch through the holder. At the selected setting, the dresser is then locked in the holder by the lock nut 79.

As seen in FIG. 4, the main arm 11 is mounted on the support shaft 6 between the adapter 8 and the set collar 20 by means of needle or like roller bearings 81 and 82. The main arm may be in the form of an I-beam extending from the hub 83 at the proximal end thereof to a similar hub 84 at the distal end thereof. Circular holes 85 may be provided in the web of the I-beam to lighten the weight of such arm. The hub 83 may be provided with a clamp screw indicated at 86 in FIG. 1 properly to lock the arm 11 in the desired position.

The outer arm 10 may be in the form of an angle having a top horizontal flange 89 and a vertically extending flange 90. The inner hub 91 is provided with a downwardly extending pintle 92 which may be journaled by needle bearings or the like 93 in the hub 84 at the outer end of the arm 11. A thrust bearing 94 is provided between the hub 91 and the top of the hub 84. The outer end of the arm 10 is provided with a vertically extending sleeve 95 and post 96 of the clamp assembly 9 passes through bronze bushings 97 and 98 in such sleeve. A centering screw bracket 99 may be held to the sleeve 95 by means of a cap screw or other suitable fastener 100 and the bottom inturned portion 101 of such bracket is provided with a centering screw 102 having a knurled lock nut 103 thereon. The tip of the screw contacts the bottom of the post 96 and in this manner the vertical height of the post may be adjusted.

It can now be seen that the arm assembly 3 provided by the inner and outer arm sections 11 and 10 is articulated about the vertical axis of the pintle 92. Moreover, the arm assembly can swing about the support shaft 6 and further, the clamp assembly can vertically swing about the axis of the post 96. Bracket 105 may be secured to the hub 91 to act as a stop limiting the amount of swinging of the arm extension 10 with respect to the arm section 11.

The skate S is held with the runner R extending horizontally by the special clamp assembly 4 which comprises clamps 110 and 111 both pivoted to hinge pin 112 extending between the arms 113 and 114 projecting upwardly from the plate 115 which is secured to the post 96. A thumb screw 116 may extend through the rearward extension 117 of the top clamp 110 to bear against the rearward extension 118 of the bottom clamp 111. A stop projection 120 on the top of the plate 115 may be provided adapted to engage the bottom clamp 9 so that the clamp with the skate secured therein will be supported by the hinge pin 112 and the stop 120 with the runner projecting in a substantially horizontal plane. The stop, however, does not preclude the operator from pivoting the entire clamp assembly to the phantom line position shown at 121 readily visually to inspect the blade or runner R.

As seen in FIG. 8, a springing bar 123 may be provided if the runner R will not align with the grinding wheel 28 throughout its entire length. Since many skate runners are bent or sprung out of line, they will have to be straightened before the parallel grinding operation on the

wheel 28 can be performed. The springing bar may comprise a bar of mild steel approximately $\frac{1}{4}$ inch by $\frac{3}{8}$ by $10\frac{1}{2}$ inches long. Holes may be drilled and tapped adjacent each end of the bar accommodating threaded thumb screws 124 and 125. The bar with proper adjustment of the thumb screws can then be used either above or below the skate runner R to swing the high end or ends up or down so that the entire length of the runner will be in alignment with the plane of the grinding wheel 28.

Operation

The operator standing behind the clamp assembly 9 places the skate S in the clamp with the toe of the runner R on the left-hand side. The grinding operation should always start at the toe and end at the heel and thus grinding will begin on the left side of the runner and end on the right side. This procedure ensures that the parallel grinding operation will be done against the rotation of the grinding wheel. The pintle pivot 92 should be kept to the operator's left throughout all of the grinding operations as the machine will originally be aligned with it in this position. The stop 105 may assist in this to render it impossible to pivot it to the right.

The first grinding operation is the cross grinding on wheel 29 and, after the skate and runner is properly clamped in the assembly 9 and vertical adjustment by means of the centering screw 102 is obtained to position the skate runner in the center of the grinding wheel 29, the clamp assembly 9 with the skate therein is swung around to the side of the wheel as indicated by the phantom line position 130 in FIG. 2. A center mark will ordinarily be provided on the grinding wheel hub shaft to assist in the proper height adjustment of the runner R.

Another way to set the vertical adjustment of the ice skate would be to align the skate runner with the center of the parallel grinding wheel, since the centers of these wheels are horizontally aligned when the grinding head assembly is in the position shown in FIGS. 1-4. After the skate blade or runner has been properly centered, the grinding head is positioned as shown in such figures and this will then center the skate for the proper cross-grinding by the wheel 29.

After the cross-grinding is completed, in the phantom line position 130 shown in FIG. 2, the arm assembly with the pintle 92 on the operator's left can be swung in the direction of the arrow 132 in FIG. 2 to the full line position. The operator may then clamp the arm assembly by means of the screw clamp 86, if desired, and with the handle 51 will release the screw clamp between the knuckle 13 and the axle shaft 14 so that the grinding head may be pivoted from its FIGS. 1 and 2 position to its FIG. 5 position. The stop screw 54 will contact the shaft 6 providing a proper stop and the center of the grinding wheel 28 should now be in the same plane as the runner held between the clamps 110 and 111.

In the second parallel grinding operation, all of the cross-grinding marks left by the first operation will be removed and the amount of hollow grind will be increased. Again, with the pintle 92 on the operator's left, the operator will check the contact point of the runner with the wheel and adjust the height of the runner if needed. The machine is, however, carefully aligned and the swinging of the skate from one center to the other will normally maintain the skate properly aligned. It may be necessary to adjust the skate height slightly due to variation in skate runner thicknesses. The operator will normally check contact at both the toe and heel since many skate runners are bent or sprung out of line. If there is too much run-out from one end to the other, the springing bar shown in FIG. 8 may be employed. Also, some skaters prefer skates sharpened with a parallel grind a little off-center so that the outside edge of the runner may be higher than the inside edge. This may also result in some height adjustment of the runner.

The operator will start grinding at the toe of the blade, moving the skate to the left against the rotation of the grinding wheel. Three or four passes should be enough to produce the finished results desired. The operator may 5 employ the tilt up clamp feature to inspect the progress and results of each pass. The finish obtained in this final operation is generally such that hand honing or finish is not required. However, extreme sharp edges may be touched lightly with a fine honing stone to eliminate the initial biting action which skaters find objectionable if the skates are too sharp.

It can now be seen that there is provided a highly versatile ice skate sharpener with which the steps of cross-grinding and parallel grinding can quickly and easily be 10 accomplished obtaining more accurate and better skating edges.

Other modes of applying the principle of the invention may be employed, change being made as regards the 15 details described, provided the features stated in any of the following claims or the equivalent of such be employed.

I, therefore, particularly point out and distinctly claim as my invention:

1. A skate sharpener comprising a pedestal, an articulated arm mounted on said pedestal for horizontal swinging movement about the axis of said pedestal, a skate holding clamp mounted on said arm adapted to hold an ice skate with the runner thereof in a horizontal plane, a grinding head assembly, a cross-grinding wheel and a parallel grinding wheel mounted on said grinding head assembly, the axes of said wheels being in the horizontal plane of such runner, and pivot means mounting said grinding head assembly on said pedestal adapted to pivot said grinding head assembly about a horizontally extending pivot axis in such plane to place said wheels to rotate in a vertical or horizontal plane, said skate holding clamp being freely movable in such horizontal plane of such runner whereby the runner of such skate may be presented parallel to the plane of rotation of said parallel grinding wheel or normal to the plane of rotation of said cross-grinding wheel.

2. A skate sharpener as set forth in claim 1 wherein said skate holding clamp comprises pivotally mounted clamp members adapted firmly to grip such skate runner along the edge thereof, means to exert a clamping pressure on such runner, and means bodily to pivot said skate holding clamp about a horizontally extending axis for visual access to the edge of the runner by the operator.

3. A skate sharpener as set forth in claim 1 wherein said skate holding clamp is provided with a vertically extending post pivotally mounted at the distal end of said articulated arm, and means vertically to adjust the height of said post with respect to the distal end of said arm.

4. A skate sharpener as set forth in claim 1 wherein said means to pivot said grinding head assembly comprises a knuckle mounted on the top of said pedestal, a knuckle axle shaft extending therethrough secured to said grinding head assembly, and stop means adapted to limit the pivoting movement of said grinding head assembly to place said grinding wheels either in such vertical or horizontal plane of rotation.

5. A skate sharpener as set forth in claim 1 including a motor mounted on said grinding head assembly for pivotal movement therewith, and belt means driven by said motor adapted to drive both said grinding wheels.

6. A skate sharpener as set forth in claim 1 including wheel dressers for the respective grinding wheels on said grinding head assembly, the dresser for said cross-grinding wheel comprising a threaded diamond mounted on a pivotally mounted support, the pivot axis for said support intersecting the axis of said grinding wheel, said parallel grinding wheel being provided with an adjustable radius-type diamond dresser.

7. A skate sharpener as set forth in claim 1 wherein

said arm is mounted on said pedestal by means of needle bearings.

8. A skate sharpener comprising an upright pedestal, an ice skate holding clamp mounted on said pedestal adapted to hold the runner of such skate in a horizontal plane, means mounting said clamp for movement in said plane to different sides of said pedestal, a grinding head assembly pivotally mounted on said pedestal about an axis substantially coincident with the plane of such runner, a cross-grinding wheel and a parallel grinding wheel mounted on said grinding head assembly, the axes of said wheels intersecting the pivot axis of said grinding head assembly.

9. A skate sharpener as set forth in claim 8 wherein the pivotal mounting of said grinding head assembly on said pedestal comprises a knuckle on the top of said pedestal, a knuckle axle shaft extending through said knuckle secured to said grinding head assembly, handle operated clamp screw means mounted in said knuckle adapted to clamp said knuckle shaft in said knuckle at the desired position, and stop screws adapted to limit the pivotal movement of said grinding head assembly with respect to said pedestal.

10. A skate sharpener as set forth in claim 8 including an articulated arm mounting said skate holding clamp, anti-friction bearing means mounting the proximal end

5 of said arm on said pedestal, a pivot joint in said arm, anti-friction means in said joint, the distal end of said arm being provided with a vertically extending socket, said skate holding clamp being provided with a vertically extending post adapted to be received in said socket, and means vertically to adjust the height of said post within said socket.

11. A skate sharpener comprising a grinding head assembly, a pair of power-driven grinding wheels on said grinding head assembly, the axes of said wheels lying in a common horizontal plane, means mounting said grinding head assembly for pivotal movement about an axis lying in such plane to pivot at least one of said grinding wheels to such horizontal plane, clamp means operative to hold the runner of such skate in such horizontal plane, said clamp means being mounted for movement in a horizontal plane.
